(57) **CLAIM**

The ornamental design for an outsole for footwear, as shown and described.

DESCRIPTION

FIG. 1 is a front perspective view along the bottom of an outsole for footwear showing my new design.

FIG. 2 is a rear perspective view along the bottom of the outsole of FIG. 1.

FIG. 3 is a bottom plan view of the outsole of FIG. 1.

FIG. 4 is a front elevational view of the outsole of FIG. 1; and, FIG. 5 is a side elevational view along the medial side of the outsole of FIG. 1.

FIGS. 1-5 depict a first embodiment of an outsole for a left shoe, a second embodiment is an outsole for a right shoe, which is a mirror image thereto.

Features illustrated with the broken lines form no part of the claimed design and are merely to illustrate an exemplary environment for the portion illustrated with solid lines.

1 Claim, 2 Drawing Sheets(56)
